EXPLOSIVE COMPOSITION

Milton F. Lindsley, Jr., Kings Mills, Ohio, assignor
or to The King Powder Company, Kings Mills,
Ohio, a corporation of Ohio

No Drawing. Application July 11, 1940,
Serial No. 344,957

2 Claims. (Cl. 52—15)

This invention is directed to new and improved explosive compositions and is a continuation in part of my copending application, Serial No. 275,497 which discloses and claims a method of making them. The invention is disclosed particularly in relation to granular, high explosive materials suitable for blasting, mining, commercial demolition and munitions purposes.

The compositions of the present invention may exhibit explosive strength from approximately 20 to 70%, as determined by the Du Pont ballistic mortar, and may exhibit packed, volumetric densities varying from approximately 0.5 to 1.2 or higher. They are characterized by the superior blasting qualities which they exhibit, that is, a more efficient result than heretofore obtainable with explosives of similar strength and sensitivity. The explosives are characterized particularly in the fact that each grain, individually, is a completely explosive composition, in and of itself.

At present, most high explosives used for commercial blasting purposes are made of intermixed ingredients such as ammonium nitrate, sodium nitrate, other oxidizing agents, fuels, stabilizers, etc. These ingredients are mechanically blended together in a suitable mixing machine, such as a dynamite mixer, and then sensitizing agents such as nitroglycerine, nitro starch, nitrocellulose or the like are added. In the finished explosive compositions the respective materials remain as individual particles in admixture.

The compositions of the present invention are granular materials in which the principal explosive ingredient is a crystalline material, such as ammonium nitrate, or mixture of ammonium nitrate and sodium nitrate, or the like. In each grain, however, this crystalline component, instead of being admixed with the other explo-

sive ingredients, the cereal, fuel, stabilizers, etc., forms a crystal nucleus or embodiment in which the other ingredients are present as inclusions. Each grain is a full and balanced explosive in and of itself, and in this respect, the compositions are distinguished from aggregates of discrete particles.

The grains also are of a porous nature and are too insensitive, in most instances, to be detonated except by the use of special or extraordinary detonators. To render such grains sufficiently sensitive for practical commercial usages the surfaces of them carry sensitizing agents, enabling the compositions to respond to detonating waves and be set off when the grains are collected into cartridges.

The compositions made in accordance with the present invention exhibit slow average speeds of detonation; for instance, 3000 to 7000 feet per second, and are highly sensitive; for example, their sensitivity may be as high as 50 centimeters, as determined by the Standard halved cartridge method (1 1/4 by 3 inch cartridges). Such results, moreover, are obtained without nitro-sensitizers, such as nitroglycerine or the like, which are objectionable because of the headaches caused by the gases from them.

Various methods may be employed for manufacturing the present compositions, and one method particularly suitable is disclosed in the aforesaid copending patent application of which this application is a continuation in part. For the purpose of assisting those skilled in the art, the disclosure of this method is repeated here.

The components entering explosive compositions, whether they be of the detonating or deflagrating kind, may be divided into two classes: (a) the materials of a crystalline nature which are liquefied or melt under the influence of heat and (b) the materials which are of solid, amor-

phous or non-liquefiable nature. Ammonium nitrate is a typical example of an explosive ingredient of the first group, while tar char, cereal, and charcoal are typical examples of the other. Other liquefiable and non-liquefiable explosive ingredients are disclosed at later points in the specification.

It is the concept of the present process first to melt or liquefy one or more of the crystallizable and liquefiable components of which an explosive is to be made. This is done preferably by placing this component part in a suitable vessel or container, and heating while stirring or agitating it until it melts or becomes of liquid or semi-viscous consistency.

Meanwhile, the remaining ingredients of the composition intended to be made, that is, the non-liquefiable components (and whatever liquefiable components that have not been melted in the preceding step) are placed in a mixer and thoroughly admixed with one another. In this operation no heat necessarily is added. Next, the melted, hot component or components, which are now in the liquid state, are added to and thoroughly incorporated with the admixed non-liquefiable components and the whole mass is stirred and agitated until all of the ingredients are thoroughly associated with each other. As a practical matter, in this operation the components preferably are associated to such a degree that they lose their individual physical identities.

The temperature or cooling is so controlled that the mass, now comprising the liquid components associated with the non-liquid components, is of a plastic nature, somewhat dough-like and tacky in consistency. Otherwise expressed, the temperature is maintained sufficiently high to avoid solidification but the temperature is below that at which the material would tend to ignite, or exothermically decompose.

In the next step the crystalline component is permitted to recrystallize, holding within it, as inclusions, the other explosive components. During such transition from the plastic to the solid state the mass is subdivided into grains. A preferred technique for accomplishing this result is to subdivide the plastic mass into particles of predetermined size by passing the mass through a screen, perforated membrane, or plate, while it still is hot.

By first melting the liquefiable components of the finished composition and then adding the non-meltable ingredients, the dangers of spontaneous ignition are avoided and the process proceeds with safety. If the fuel, oxidizing and binding agents were to be associated with the crystalline nitrate, and the whole mass then heated to liquefy the latter, spontaneous ignition would occur almost certainly; the danger, at least, would be so great as to preclude any practical usage of the idea. On the other hand, if the ammonium nitrate, or other meltable components, be first melted and then this mass be added to, and incorporated with, the remaining materials, the temperature at no time approaches the temperature at which ignition might occur. The relatively high temperature required for melting the liquefiable materials prevails only during the period of safety, and decreasing or relatively low temperatures, are employed during the otherwise dangerous phase, that is, when all of the components are being admixed with one another and when a finished explosive composition is being operated upon. This safety feature is based upon the fact that the meltable compo-

nents used in explosives manufacture, either hot or cold, are relatively stable in and of themselves but their stability decreases as the other materials are admixed with them. In the present process, the relatively increasing instability of the mass, as the materials become more intimately associated, is offset by permitting the mass to cool and the temperature to decrease during this phase.

10 Briefly, therefore, this process for making the products may be said to comprise destroying the crystalline nature of the crystalline component, then incorporating therein particles of the other explosive ingredients, and finally subdividing the mass and recrystallizing the crystalline component so that it holds the particles of other ingredients as inclusions.

For forming of the grains of finished explosive the temperature of the mass is controlled so that it is of a plastic doughy nature. 20 To subdivide this mass into granules it is forced through a screen or perforated membrane which serves to provide discrete, granular particles. The plastic mass, before subdivision, dissipates its heat quite slowly. However, the ratio of the surface area to volume of the subdivided particles emerging from the forming membrane is much greater. These particles, therefore, lose their plastic nature and become set in their physical form quite quickly. In some instances a thin or hard casing is formed upon the particles. The rapidity with which the particles become set is dependent largely upon the temperature of the atmosphere surrounding them as they emerge from the forming screen or membrane. The particles, therefore, retain their individuality sufficiently to permit them to be sorted as to size, packed, or treated with surface sensitizing material without waiting for them to cool completely. 40 As a matter of economy, the very fine particles and any lumps or large particles are recovered and later admixed with the non-liquefying ingredients to which the liquefied ingredients or components are to be added in the manufacture of a subsequent batch of the material.

In the present description, the material melted is termed the liquefied or meltable compound. This designation is intended to include inorganic metallic nitrates, meltable carbohydrates having usage in explosives manufacture, and materials of similar function. Combinations of materials which tend to form eutectic mixtures melting at lower temperatures than the components of them preferably are used to avoid unnecessarily high temperatures. For instance, admixtures of ammonium nitrate, sodium nitrate, sugar, dextrose and the like may be used, both for the purpose of lowering the melting point of the mixture and for the purpose of contributing to the chemical composition and physical characteristics of the explosive itself. This term also is intended to include such materials as starches, carbonates, resins and gums which function in the finished explosive compositions as stabilizers or fuels. All of these materials are characterized in that their use in the manufacture of explosives is recognized by those skilled in the art, and in that they, or combinations of them, melt to become fluid or viscous when heated to temperatures below the temperatures of decomposition or ignition.

In this description the term non-meltable or non-liquefiable ingredients is intended, as the term implies, to designate the materials entering the explosive composition which do not melt or liquefy under the influence of heat. Typical ma-

terials of this group are coal, charcoal, cereals, wood pulp, starch, metallic sensitizing agents, etc.

In addition to these solid and meltable materials, there is a group of materials used in explosives manufacture which are liquid at room temperature or have very low melting point. Paraffine, mineral, vegetable and animal oils, and explosive organic nitro compounds are typical of this group. They are not compatible with the materials of the melt, nor safe to be heated with it. When such materials are to be used they are best added after or as the melted and non-meltable materials are incorporated with each other.

As previously disclosed the present explosive compositions are adapted to be used for commercial blasting demolition purposes for coal mining, or for similar purposes where materials of the permissible type as well as materials of sustained heaving power are desired, and for use in munitions. In the examples which follow the various materials are melted and the materials which are of non-liquefiable nature are classed under the following headings.

Representative compositions for general blasting purposes

	Low explosive granular or pellet	Low explosive granular or pellet	High explosive	High explosive	High explosive	High density high explosive (loaded 1.13)	Low density high explosive (loaded .59)	High explosive without waiting for large diameter
Melting materials:								
Ammonium nitrate	15		63.5	87.5	58.5	57.0	84.5	53.5
Sodium nitrate	60	70	29.0	29.0	29.0	27.5		27.5
Sugar	3	6	2.5	6.0		3.0		3.0
Dextrine							4.0	
Other ingredients:								
Sulphur	10	11.5	3.0	2.0	3.0	3.0	1.5	3.5
Paraffine			6.0		8.5	1.0		
Tar char					7.0			5.0
Charcoal	9	9.5						
Wood pulp	3	3					9.0	2.5
Aluminum			1.0	1.0	1.0	1.5	1.0	
Total	100.0	100.0	100.0	100.0	100.0	100.0	100.0	100.0
Strength			40%		60%	40%	60%	40%

The densities of the compositions adapted for these purposes may vary from approximately .59 to 1.13.

Explosives for coal mining

The density of explosives for coal mining and similar purposes is preferably about 0.8. A typical example of a permissible type high explosive is as follows:

Melting materials:

Ammonium nitrate	34.75
Sodium nitrate	6.5
Sugar	2.0
Dextrine	

Other ingredients:

Sulphur	1.5
Paraffine	
Tar char	
Charcoal	
Wood pulp	3.0
Aluminum	2.25

Total 100.0

Such a composition has been accepted as permissible by the United States Bureau of Mines.

The experience gained in the field with the use of compositions of the present invention for coal mining purposes, indicates that they uniformly exhibit from 5 to 25% more blasting efficiency than materials of the type heretofore available

of similar strength, that is, more tons of lump coal of the desired formation are obtained per pound of explosive than is otherwise obtainable with conventional materials. There is a substantially lesser percentage of slack due to the sustained heaving action exhibited by the materials and they are not injurious to the roofs of mines, particularly in instances where slips exist. In substance, the "spread" produced by the materials is comparable to that of black powder and this result is obtained without the use of nitro explosive ingredients which give off toxic gases which affect the workmen by causing headaches.

Munitions explosives

A composition adapted particularly for use for munitions purposes is as follows:

Melting materials:

Ammonium nitrate	37.5
Sodium nitrate	6.0
Dextrine	

Other ingredients:

Sulphur	2.0
Paraffine	
Tar char	2.5
Charcoal	
Wood pulp	1.0
Aluminum	1.0

Total 100.0

In explosives for this purpose it is desirable that the density be approximately 1.2 to 1.5. It has been determined that the present compositions, instead of being surface sensitized with a metallic sensitizer of the type of aluminum, may be treated with from approximately 3 to 20% of tri-nitro toluene which is of a melted consistency but insufficiently fluid to penetrate deeply into the grains. For making such compositions the tri-nitro toluene is added to the plastic mass at the time it is being subdivided and preferably before the grains have set to hard solid state. The plastic grains carrying the sensitizer are charged into the shell or cartridge and are of such plasticity that they readily conform to one another to provide the desirable high density, especially if the shells or cartridges be vibrated. Afterwards, when the explosives are permitted to cool in the cartridges each grain carries its own sensitizer on its surface and the grains remain individually discrete so as to be readily detonatable. In place of the wood pulp employed in the

foregoing compositions ivory meal, cereals, bagasse, almond shells, corn meal, rice hulls and other carbonaceous fuels may be used. The aluminum employed in the foregoing compositions serves as a sensitizing agent. Where control of the speed of detonation of the ultimate composition is desirous, in conjunction with the control of the sensitivity, the aluminum may be of powdered form and applied as a surface sensitizing material in accordance with Lindsley Patent No. 2,126,401, issued August 9, 1938. Otherwise, the aluminum may be incorporated directly with the other nonmeltable material; compositions similar to Ammonal may thus be prepared. In place of aluminum as a surface sensitizing agent other sensitizing ingredients also may be employed, for instance, as described in the aforesaid patent.

The sulphur, paraffine, charcoal, wood pulp and other ingredients fulfill their usual functions in the explosive compositions.

From the point of view of physical structure, each explosive grain is a relatively porous particle, with sensitizing material applied to its exterior surface. The material at the inside of the grain is relatively insensitive, that at the surface, on the contrary, is very sensitive and, therefore, responds promptly to a detonating wave. The composition of the material at the surface of each grain lends to decomposition and detonation in the material at the interior grain, since the two are essentially integral with one another.

In the explosive grain, the crystalline sodium nitrate or ammonium nitrate, or a mixture of these which may be used, is a substantially continuous phase, even though it is of a porous nature, and the other explosive ingredients, the fuel, stabilizer, etc. are present in the crystalline phase as inclusions surrounded by it. The mass of each grain is, therefore, distinguished from an explosive in which the particles of the various components reside, at best, only adjacent one another, depending upon the degree of compaction and mixing employed at their preparation.

The porosity of the materials makes them adapted particularly to the reception of surface coating sensitizing substances, such as powdered aluminum or the like. Very small quantities of sensitizing material can be distributed over the surface to obtain the desired sensitivity, for instance, approximately $\frac{1}{2}\%$ to 2% by weight. Even with so small a quantity of sensitizing, the compositions nevertheless have a sensitivity as great as 50 centimeters as determined by the halved cartridge method. In contrast, sensitivities of 5 to 10 centimeters have been considered good in the past for ammonium nitrate explosives.

One of the characteristics of the explosives of the present materials which is not fully explained by the present knowledge concerning explosive decompositions is the fact that the present materials respond differently according to the environment in which they are detonated. To a greater degree than has been exhibited by any of the materials heretofore available with which I have been familiar, a given explosive composition of the present invention will exert a relatively slow and sustained heaving action if detonated in a soft medium like coal, and yet detonate briskly if a similar charge be fired in hard rock. It is believed that one reason which may account for this result is that the interior of the grains is substantially insensitive though potentially de-

tonatable, while the surface sensitizing in and of itself may be, or otherwise forms with the explosive at the surface of the grain a very sensitive material. The response of a potentially explosive composition is determined by the chemical composition as well as the physical environment. The physical environment of an explosive, as determined by the pressure or the heat to which it is subjected, affects its sensitivity by upsetting chemical equilibrium and thereby increasing sensitivity toward detonation. Conventional explosive materials of the type heretofore available have been uniformly sensitive throughout their mass, whereas in the present compositions the insensitivity of the interior portion of each grain enables it to respond in accordance with the pressure and heat of its environment. In a hard rock pressure and heat are substantially greater than in a soft coal or friable shale; in the latter the gases escape more readily. Consequently, the insensitive nature of the grain is offset to a greater degree in hard rock blasting than in coal mining or like operations.

The grains of the explosives produced by the process may be packed immediately, as previously described, they may be surface coated and then packed, or they may be fed into a pelleting press after which the usual procedures are followed. The granules of material also may be further sensitized by the impregnation of them with liquid nitro explosives in a process of the type employed in the manufacture of present day dynamite. When this is done, the sensitivity is augmented, but with corresponding increase in the speed of detonation.

Most of the components of the typical granular explosive compositions are poor conductors of heat. If all of the components of a given explosive are admixed and then heated, local portions, for instance, those adjacent the walls of the heating vessel, become overheated and initiate exothermic decomposition of the mass as a whole. By first melting the components which will liquefy under the influence of heat, in the absence of the other materials which will not liquefy, the dangers of overheating are avoided since the heat is transferred more readily throughout the mass as it becomes fluid. The liquid mass, in turn, is very easy to incorporate intimately with other materials. A recognition of this differentiation is important in the practice of the invention.

In making the melt, raw materials of commercial moisture content are used, and pre-drying of them is not necessary since the heating tends to drive off the moisture. In some instances the addition of a small quantity of moisture, for example, up to about 1% of the materials being melted, is employed for the purpose of decreasing the time required to make the melt. This added quota of water serves as a conductor of heat to the interior of the mass; it is driven off as the melting proceeds, sufficiently that the finished explosive need not be subjected to the usual drying process. Explosive grains made by the process, but intended to be made into pellets, may contain up to about 6-8% of water; this water may be added at the time the melt is being made, but, of course, it must be removed after the pellets have been formed.

Ammonium nitrate alone melts at a temperature of about 305° F. The addition of sodium nitrate to the ammonium nitrate decreases the temperature at which the mass melts by forming or tending to form eutectic mixtures. Material

such as sugar and dextrine may be used in place of the sodium nitrate or in conjunction with it for the same purpose.

It is preferable to employ a steam jacketed kettle for melting the materials to avoid open flames and to provide for better control of the temperature. The steam jacketed kettle is equipped with a mechanical mixer or agitator for stirring the material.

In mixing the ingredients to which the melt is to be added, a trough or dough-type mixer is suitable. The non-meltable components are placed in the trough and commingled until the mass in the trough is of uniform consistency. The trough may be jacketed, either for the application of steam to it in order to prevent too rapid cooling of the mass after the melted material is added, or for the application of cooling water to lower the temperature. When the proportion of melted material to the whole is relatively high, the mass obviously is of a very plastic nature. In some instances, it may be too liquid to be formed easily into grains by the forming membrane, and in these cases cooling water is applied after the components have been mixed thoroughly. On the other hand, when the proportion of melted materials to the whole of the mass is relatively low it may tend to set or congeal very quickly. In this case the mixing trough may be warmed by the application of steam to the jacket to prevent the mass from congealing into hard lumps before it is formed into grains.

Improperly sized particles of finished explosive made during a previous run may be added and admixed with the non-meltable materials. It is best to do this prior to the addition of the melted components.

The admixture of meltable materials and non-meltable materials constitutes a finished explosive in the plastic state which is ready to be formed into grains. This dough-like substance next is conveyed from the mixing trough to the forming membrane and formed, preferably as promptly as possible, and permitted to crystallize and harden into grains of finished explosive.

By controlling the temperature of the atmosphere upon the side of the forming membrane at which the grains emerge, the rapidity with which they congeal and set into physically hard particles may be controlled. Some plastic explosive masses have a much higher latent heat than others; this factor depends largely upon the nature of the ingredients of which the explosive is made, and, to a lesser degree, upon proportions. If the grains be expelled into a chilled or frigid atmosphere, then a hard casing upon them is formed quickly, and the particles, although frangible, retain their individuality sufficiently for them to be sized and sorted in the usual riddle as they emerge from the forming operation. In such instances the granules present jagged, somewhat crystallitic surfaces. These surfaces are particularly adapted to receive surface sensitizing agents and provide highly sensitive explosive compositions.

In other instances granules of relatively smooth, rounded surface are desired. In such cases, the temperature prevailing as the grains are formed can be somewhat higher so as to prevent the particles from setting and congealing too quickly. If such particles are passed directly after their formation the mechanical riddling action tends to smooth the outer surfaces.

For explosives intended for blasting and com-

mercial demolition purposes the forming membrane may be a screen having openings approximately 3 x 3 to 14 x 14. In place of employing a screen or foraminous membrane for forming the grains, extrusion machines or pelletizing machines may be used.

It usually is not necessary to dehumidify the atmosphere at the discharge side of the membrane though this may be desirable in the summer time, or during rainy seasons when the humidity of the air is very high. In the winter time the air may be heated, if necessary, to prevent the particles from being chilled too rapidly.

The manner in which the grains are formed in the process of the invention, as previously explained, enables highly sensitive explosive compositions to be made. The surfaces of the granules are particularly receptive to sensitizing agents of the type of aluminum. One explanation of this feature may reside in the fact that there is greater intimacy of contact between the surface sensitizing agent and the surface of the grain, due to the nature of the surface of the grain as provided by the process through which it was formed. While the sensitivity of 50 centimeters, or greater, as determined by the Standard halved cartridge method, may be obtained without the use of nitro glycerine or nitro glycol sensitizers, the grains may be treated with such nitro sensitizers if desired.

A detailed example of the employment of the process in the manufacture of an explosive is as follows:

To make, for instance a 40% strength granular explosive, 58 parts of ammonium nitrate, 27 parts of sodium nitrate and 3 parts of sugar are introduced into the melting chamber, steam at a pressure of 5 pounds is introduced into the jacket and the materials are stirred and agitated and heated until they are melted. This operation usually will require about 10 minutes. Meanwhile, 3 parts of sulphur, 7 parts of wood pulp, and 1 part of paraffine are introduced into the trough and admixed. When the melt is completed it is added to the trough and both groups of components are admixed.

The temperature is so controlled that when all of the components are admixed the temperature of the plastic mass is approximately 100° C. It is then discharged gradually into the grain former.

Air at room temperature (80° F.) at relative humidity of 5% is admitted to the riddle. After the material is classified it may be treated with approximately 1% of aluminum powder in a glazing tumbler and it is then ready for use.

While the process just disclosed is preferred for the manufacture of the materials of the present invention because of the ease and low cost of manufacture which it provides, the materials can also be made by a process in which the ammonium nitrate, with or without other crystallitic materials, is dissolved in water so as to provide a saturated solution. The other explosive ingredients, the fuels, stabilizers and so forth, are next incorporated in this solution and the water then removed by evaporation, preferably under reduced pressure. As water is removed the ammonium nitrate crystallizes and the other ingredients are included in the crystals. This process is not the full equivalent of the one previously disclosed because of the expense involved in the removal of water and the relative difficulty of controlling grain size and obtaining the requisite porosity. It is suitable where specialized

compositions are required and is disclosed as a partial equivalent to the process previously illustrated.

The foregoing details, as well as the explanation proffered to explain the reasons for the present improvement, are given to illustrate the advance, and the invention is not limited thereto but only by the substance of the claims which follow.

Having described my invention, I claim:

1. A detonating explosive comprising a mass of discrete grains each constituting a balanced explosive composition and comprising a crystalline substance including a substantial quantity of ammonium nitrate as a continuous phase, and fuel and oxidizing agents residing within the continuous phase as inclusions, the external portions of said grains being of a hard and dense nature and having metallic sensitizers intimately associated therewith to the extent of from approximately $\frac{1}{2}$ to 2% by weight of the grains as a whole, while the interior portion of each grain is porous and permeated with cracks and fissures and is substantially insensitive, the sensitivity of the mass of grains as a whole being as high as 50 centimeters as determined by the halved cartridge method using $1\frac{1}{4}$ by 8 inch cartridges.

2. A detonatable explosive composition comprised of a mass of discrete grains, each discrete grain being in and of itself a balanced explosive and having ammonium nitrate as its principal explosive component but also having fuel and oxidizing components associated therewith, the ammonium nitrate component of the grain forming a substantially continuous phase with the fuel and oxidizing components being present in the continuous phase as inclusions, with pores permeating the continuous phase but with the surface of the grain being dense and compact and having thereon a metallic sensitizing agent, the porous continuous phase of the explosive being substantially insensitive to detonation while the surface sensitizers form with the dense compact surface of each grain an explosive composition sufficiently sensitive that the mass as a whole has a sensitivity of as high as 50 centimeters as determined by the halved cartridge method using cartridges $1\frac{1}{4}$ inches by 8 inches, the porosity of the grains enabling the grains to provide a relatively slow heaving action in soft stratum.

25

MILTON F. LINDSLEY, JR.
